(57) **CLAIM**

The ornamental design for a recreational vehicle cover, as shown and described.

DESCRIPTION

FIG. 1 is a front elevation view of a recreational vehicle cover showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof with the recreational vehicle cover in a first state;

FIG. 8 is a second perspective view thereof with the recreational vehicle cover in a second state and covering a recreational vehicle;

FIG. 9 is a third perspective view thereof with the recreational vehicle cover in the second state;

FIG. 10 is a fourth perspective view thereof with the recreational vehicle cover in a third state;

FIG. 11 is a fifth perspective view thereof with the recreational vehicle cover in a fourth state; and,

FIG. 12 is a sixth perspective view thereof with the recreational vehicle cover in a fifth state.

The broken lines shown in the drawings are for the purpose of illustrating portions of the recreational vehicle cover or the environment of a recreational vehicle that form no part of the claimed design.

1 Claim, 12 Drawing Sheets
